UNITED STATES PATENT OFFICE

2,576,520

HYDRAULIC CONTROL OF VENEER SLICING MACHINES

Louis F. Koss, Indianapolis, Ind., assignor to Capital Machine Company, Indianapolis, Ind., a corporation of Indiana

Application November 4, 1948, Serial No. 58,323

4 Claims. (Cl. 144—178)

1

This invention relates to a veneer slicing machine and particularly to that type of machine as illustrated in applicant's prior Patents Nos. 2,184,862 and 2,303,213, wherein the log or flitch is clamped on a diagonally upright reciprocating table between upper and lower dogs, and a slicing knife carried by an extremely heavy bed is progressively moved horizontally toward the log for successive slicing operations.

The invention herein shown and described relates primarily to controls of the operation of the machine, and primarily to the hydraulic control. By reason of the use of the present invention, the machine may be operated at speeds far above those previously employed, namely above fifty strokes per minute.

The present invention in addition to initial hydraulic dogging operations to secure the flitch on the table, includes the automatic control of the moving parts wherein the table is almost instantaneously stopped upon a condition where the log might slip slightly to extend further from the table than it should for a successive cut in such a condition where the knife might jam under the log; a condition which prohibits the inching up along the table of the dogs once they are set on the log; and for the condition where the log might fall off the dogs or a pipe fitting or hose in the hydraulic system break. In the two conditions where the knife may jam under the log, or there be a break in the hydraulic system, or the log itself fall off from between the dogs, the invention provides for a control whereby the driving motor reciprocating the log up and down the table guides is immediately cut off from the electrical power and at the same time a brake is applied to stop the entire mechanism.

These and many other objects and advantages of the invention including the extreme ease provided for handling the various operations, the high degree of safety to prevent breakage of the machinery in case of any one of the foregoing conditions occurring, all permitting the speeds of operation far above those previously employed, will become apparent to those versed in the art, in the following description of one particular form of the invention as illustrated in the accompanying drawings, in which

Fig. 1 is a view in front elevation of a machine embodying the invention but with the knife cutter bed removed;

Fig. 2, a view in rear elevation;

Fig. 3, a view in right-hand end elevation;

Fig. 4, a diagrammatic representation of the means for applying the brake;

2

Fig. 5A, a view diagrammatically illustrating the left-hand portion as viewed from the rear of the machine of the hydraulic control system;

Fig. 5B, a diagrammatic representation of the right-hand end portion of the hydraulic control system as viewed from the rear of the machine;

Fig. 6, a view on an enlarged scale through a check valve;

Fig. 7, a view in vertical central section through a control valve;

Fig. 8, a view in horizontal central section through the same valve; and

Fig. 9, a wiring diagram of the electrical control.

15 Referring to the drawings in which like characters of reference indicate like parts throughout the several views, a bed 50 supports a driving motor 51 which through a system of gearing 52 reciprocates the flitch table 53 along the inclined guides 54, 55, and 56. On the bearings 57 and 58 is supported the bed plate 59 which carries the usual cutting knife. The knife carrier 59 is advanced and retracted from the face of the table 53 in the usual manner through the lead screw shaft 60. Then on the front face of the table 53 there are mounted a plurality (eleven in the present showing) of sets of dogs, a lower dog 61 and an upper dog 62 in each set, both vertically reciprocable between the spaced guides 63, 64, and 65.

All of the construction so far described is shown in the two prior U. S. patents to which reference has above been made.

A primary control valve 10 is employed which 35 will serve to control seven of the pairs of dogs 61, 62, as will be presently described.

A pump 8, Fig. 5A, is employed to produce a relatively high pressure on the order of eight hundred pounds per square inch and above, but 40 with a relatively low volume flow. This pump 8 takes oil from a tank 23 through an intake pipe 7 and delivers it through a pressure regulator valve 9 into the supply pipe 11 which discharges to the valve 10. This valve 10 is provided with a 45 pair of pistons 2 and 3 spaced apart along an operating piston rod 1 which is externally connected to an operating lever 1a. These two pistons 2 and 3 may be slidably reciprocated within a cylinder 4 which is axially mounted within the valve body 10a to extend across a number of chambers provided in that body. This cylinder 4 opens at its ends respectively into the chambers 22b and 22c which are interconnected by the passageway 22a opening out into a discharge or exhaust pipe 22, this pipe 22 being car-

ried back to discharge into the tank 23. The pressure supply pipe 11 discharges into a central body chamber 11a, and the cylinder 4 is provided with ports 4a to provide communication from that chamber 11a to inside of the cylinder 4. In like manner, this cylinder 4 is provided with ports 4b opening into the chamber 21a and ports 4c opening into the chamber 12a. These chambers 12a and 21a respectively are interconnected with the pipes 12 and 21.

Assuming that the table 53 is stationary, and that it is desired to place a log upon the table between the various sets of dogs 61 and 62, the initial operation is to spread apart those dogs 61 and 62 in each of the eleven sets illustrated.

To do this, the valve 10 is manipulated to have the pistons 2 and 3 in those positions as illustrated in Figs. 7 and 8. The pump 8 is set into operation to supply oil under pressure to the valve 10 as previously described. The oil entering the chamber 11a flows into the inside of the cylinder 4 through the ports 4a and discharges from that cylinder between the pistons 2 and 3 through the ports 4c to have that oil flow out through the pipe 12. Referring to the diagram, Fig. 5A and 5B, this pipe 12 is interconnected to a manifold pipe 13 horizontally disposed along the rear sides of pairs of vertically disposed cylinders 16, 17 with the interspersed pairs of like cylinders 28, 29 between the pairs of cylinders 16, 17. In this regard, there is shown to the left end, Fig. 5A, a pair of cylinders 16, 17; next a pair of cylinders 28, 29, and a second set of cylinders 16, 17; next a third set of cylinders 16, 17; followed by a second occurring pair of cylinders 28, 29 (Fig. 5B); next a single pair of cylinders 16, 17; a single pair of cylinders 28, 29; two pairs of cylinders 16, 17; then a pair of cylinders 28, 29; and finally on the end a pair of cylinders 16, 17. In other words, there are seven pairs of the cylinders 16, 17 and four pairs of the cylinders 28, 29. The seven pairs of cylinders are employed to be the primary means for dogging the log, and the four pairs of cylinders 28, 29 are auxiliary cylinders to follow up in the dogging operation to provide further securing means along the log in spaced relation, the secondary four pairs operating in the same manner as the primary pairs of cylinders 16, 17 as will be further explained.

In each of the cylinders 16 there is provided a piston 70 which is connected to the connecting rod 71 in turn extending downwardly from the cylinder to the dog 61, this being the dog which is to be pulled up against the underside of the log, and consequently the cylinder 16 is in the present showing provided to have a larger diameter than that of the cylinder 17. Then the cylinder 17 is provided with a piston 72 therein connected to the connecting rod 73 which extends downwardly to engage with the dog 62, this being the dog which is pushed down on top of the log whereby the log is interengaged between those sets of dogs 61, 62. The cylinders 28 and 29 are exact duplicates of the cylinders 16 and 17 respectively and therefore have the same pistons 70 and 72 carried therein interconnecting with the lower extending rods 71 and 73 to their respective dogs 61 and 62.

From the manifold pipe 13 there is provided a pipe 14 interconnecting the pipe 13 with the upper ends respectively of the cylinders 16 in each instance. Likewise from the pipe 13 there is a pipe 15 connecting with the lower ends of the cylinders 17. Therefore when oil is applied

through the pipe 12, that oil will flow into the upper and lower ends respectively of cylinders 16 and 17, and thereby drive the pistons 70 and 72 to their respective lower and upper ends whereby the dogs 61 and 62 are spaced apart one from the other their major vertical distance permissible.

Since the hydraulic system is a closed system, there will have been oil on the opposite sides of those pistons 70 and 72, and this oil escapes respectively from the lower end of the cylinder 16 and the upper end of the cylinder 17 through the pipes 18 and 19 respectively interconnected with the horizontally disposed manifold pipe 20. The pipe 21 is interconnected between the pipe 20, herein shown as at the left-hand end, Fig. 5A, and the valve 10 to communicate with that chamber 21a therein. Thus oil flowing toward the valve 10 can flow through the ports 4b into the cylinder 4 and out the end of that cylinder into the chamber 22c, and flow through the interconnecting passageway 22a to discharge through the pipe line 22 back into the supply tank 23. Attention is directed to the fact however that interposed in this pipe 21 there is a check valve 20a which is illustrated in detail in Fig. 6. Normally the flow just described of the oil through the pipe 21 would be prevented by reason of the fact that the poppet valve 74 is seated and normally remains seated by means of an extremely light coiled spring 75 operating between the underside of the valve body and a piston 76. Oil pressure in the upper end of the cylinder 16 will be communicated through a tube 77 leading from that end of the cylinder 16 to the underside of the piston 76 so that the pressure in the cylinder 16 will tend to lift the poppet valve 74. By reason of the fact that the pipe 21 which would then be the outlet of the relief or check valve 20a is interconnected through the valve 10 to the atmospheric pressure at the tank 23, this piston 76 may lift the valve 74 to permit the flow of oil from the opposite end of the cylinder 16 out through the pipe 21. In other words this opening from the one cylinder 16 will serve to open the valve 74 which is otherwise normally seated.

A second valve 25 is employed to control the sets of cylinders 28, 29 in exactly the same manner. In this case, oil under pressure flows from the pipe 11 through the pipe 31 across through the valve 25 and out through the pipe 26 to enter the horizontally disposed manifold pipe 27. This pipe 27 is interconnected respectively between the top end of the cylinder 28 and the lower end of the cylinder 29 by the pipes 30 and 31. The opposite respective ends of these cylinders 28, 29 are interconnected through the pipes 33 and 34 with the horizontally disposed manifold pipe 32. From the pipe 32 there is the return pipe 35 leading back down to the valve 25 to permit flow of oil into that valve and across out through the discharge pipe 36 to the exhaust pipe 22 and finally to the tank 23.

Thus with both valves 10 and 25 operated as described, all of the dogs in all of the pairs will be fully spread apart so that the log or flitch (not shown) may be placed up against the table in the desired position, preferably diagonally thereacross, and held while the handle of the valve 10 is shifted for further operation of these dogs 61, 62.

To accomplish the dogging action to engage the dogs 61, 62 with the log, the pistons 2 and 3 are shifted to have the piston 2 come to the opposite end of the cylinder 4 from that shown

in Figs. 7 and 8. Of course the piston 3 being fixed to the rod 1 is carried therealong and positioned accordingly.

With the valve then conditioned as indicated, oil under pressure enters the chamber 11a from the pipe 11 and flows out through the ports 4a into the cylinder 4 and then out through the ports 4b into the chamber 21a. From the chamber 21a there leads a pipe 21 which is carried back to the check valve 20a, this being the same pipe as previously described and interconnecting with that valve. In other words oil is now flowing under pressure through that pipe, and across through the valve 20a, lifting the poppet valve 74, and entering into the manifold pipe 20. Thus the pipe 20 is now under pressure, this pressure being built up to the order of around eight hundred pounds per square inch or even above. The pressure in the pipe 20 is communicated to the lower and upper ends respectively of the cylinders 16 and 17, thereby driving up the piston 70 and driving down the piston 72 to cause the clamps 61 and 62 to interengage the log on the table therebetween. When the dogs are firmly set against the log, and there is no additional flow of oil from the pipe 21 into the pipe 20, the poppet valve 74 becomes seated, or at least it becomes seated against any tendency of return flow of oil back from the pipe 20 through the valve 20a. As will be noted in the diagram, Figs. 5A and 5B, there are additional check valves 38, 39 and 40 interspersed along the manifold 20 to serve the same purpose as does the valve 20a. These valves are provided in addition to valve 20a for the reason that the manifold pipe 20 is of relatively long length, and it is desired that the pressure be maintained constant in that line 20 after the dogs 61 and 62 have engaged the log therebetween. The slight minor shifting of the set of dogs at any one position would thus not change the pressure materially in the line 20 in respect to the pressure applied at other pairs of dogs 61 and 62.

When the pressure has been applied to the manifold 20, and the pistons 70 and 72 start going up and down respectively in the cylinders 16 and 17, oil of course must be removed from the opposite ends of those cylinders 16 and 17 to permit that travel. In this case, the oil is discharged from the top end of the cylinder 16 to the pipe 14 and from the bottom end of the cylinder 17 to the pipe 15 so that the return flow is to the common manifold 13. Pressure escapes from this pipe 13 to the pipe 12 by flow of oil therethrough back to the valve 10 and across the chamber 12a through the ports 4c then uncovered by the piston 3 and out the end of the cylinder 4 into the chamber 22b and thence around through the chamber 22a and out the exhaust line 22 back to the tank 23.

There is provided a major relief valve 41 placed in a line 80 which is interconnected with the pipe 20 at various intervals between the different check valves 20a, 38, 39, and 40. Pressure is thus transmitted from the manifold pipe 20 to the relief valve 41. This valve is normally set to remain closed up to pressures eight hundred pounds per square inch or thereabove as may be selected. The relief flow from that valve 41 is had through a pipe 81 back to the manifold 13 so that the oil in excess pressure may flow back through the pipe 12 and through the valve 10 to the tank 23 as just described. There is the possibility at times of a log or flitch tending to slip from between the dogs, but still not drop entirely out from there-

between. In this condition, the log would extend itself into the path of the knife to such a degree that it would tend to become jammed over the knife. In this regard, there is a force of some twenty-five thousand pounds to be stopped before damage is done to the knife or to the carriage and its operating mechanism. When this condition occurs, and the log comes down on top of the knife, there of course is a resistance built up to further the travel of the carriage, and this is reflected through the dog 62 primarily to tend to increase the pressure in the manifold line 20. To take care of this situation and stop the machine at once, there is provided a pipe line 41 leading from the pipe 20 from the normally closed side of the check valve 20a. This line 41 leads back to a high pressure controlling switch 42. The switch in this mechanism is in a circuit so designed as to open the circuit leading to the driving motor 51, see Fig. 9. The building up of the pressure which would be communicated through this line 41 acts almost instantaneously to trip the switch in the unit 42. Incidentally this unit 42 is of the usual and well known construction where a switch is to be operated by differences in pressure, and hence the details of the mechanism are not herein shown.

Simultaneously with the operation of the high pressure controlled switch unit 42, the winding of a solenoid 83, Fig. 4, is deenergized to lift the latch 84 out of the notch 85 in a horizontally disposed rod 86 carried in the present form inside of a cylinder 87 to have an end portion 88 carry a roller 89 in the path of the usual brake lever 90. When the latch 84 is lifted, the bar 86 may travel toward the lever 90 by reason of the pressure exerted by the spring 91 carried against an abutment 92 fixed on the rod 86 and bearing against a stop 93 placed within the tube 87.

This brake lever 90 is normally hand operated, but in the emergency just described, the bar 86 through the pressure of the spring 91 operates the lever 90 to a brake applied position.

As indicated in Figs. 3 and 4, the brake 90 is fixed to a shaft 94 which carries a lever 95 in turn rockably connected to a brake rod 96. The brake rod 96 is rockably connected to a lever 97 pivoted on the pin 98 to a fixed member such as a portion of the base 50. The lever 97 has the other end secured to a brake band 99 which wraps around a brake drum 100 that is carried in fixed position adjacent the drive gear 52a of the gear system 52. The other end of this brake band 99 is carried back into a fixed connection with the face 50, herein shown as being secured under the bracket 101 on which the lever 97 is pivoted. By reason of the relatively large diameter of the brake drum 100, the band 99 requires but slight pull by the lever 97 to apply the braking action sufficient to bring the entire mechanism to a very quick stop. This brake of course is applied simultaneously with the disconnecting of the motor 51 from the power circuit by the action of the high pressure switch unit 42. Thus through the slight degree of upward travel permitted by the upper dogs 62, to build up the increased pressure to apply a surge in effect to the high pressure switch unit 42, the table 53 is almost instantaneously stopped in its downward travel, and at least before any damage is done. The motor 51 has to be manually started before the table is again reciprocated, and this of course permits correcting the difficulty. There is also the possibility of a log becoming entirely disengaged from the dogs 61,

and 62, or a pipe fitting or a pipe line or a hose connection breaking. In this case, there is a different type of surge set up in the hydraulic system. With the quick reduction in pressure which would be occasioned by the dogs 61 and 62 relatively travelling one toward the other, or with a pipe line break, more flow of oil would be tended to be set up through the pipe line 21, but since the pump 8 is limited in its volume of flow, the pressure in the line 11 is instantly reduced. In this case, the low pressure operated switch unit 105 is operated to break the circuit between the power source and the driving motor 51, and the solenoid 83 is again operated to permit the bar 86 to apply the braking action through the band 99 as above described, thereby again bringing the entire mechanism to a quick stop.

Therefore it is to be seen that there is provided a relatively simple hydraulic control of the slicing machine to such an extent at least that the table 53 may be reciprocated at a speed far above that heretofore possible because the controls are such that the machine may be stopped before it is damaged beyond repair.

It is to be borne in mind, that as above indicated, there are enormous forces to be controlled in a machine of this type. As above indicated, the log plus the table and other associated elements will weigh around the neighborhood of twenty-five thousand pounds, and this is no little mass to be stopped almost instantaneously. This however is made possible by reason of the unique hydraulic control system above described. Moreover where these machines go out into remote places far removed from sources of transportation and supply of parts, it is highly important that the machine be kept in operating condition because it requires an exceedingly long time to get repair parts and replacement parts to the user.

Therefore while I have herein described and illustrated my invention in the one particular form, it is obvious that various changes may be made such as in the specific piping arrangement, all without departing from the spirit of the invention, and I therefore do not desire to be limited to that precise form beyond the limitations which may be imposed by the following claims.

I claim:

1. In a veneer slicing machine having a vertically reciprocating flitch table driven by a motor, a plurality of pairs of opposing dogs independently shiftable over the table, hydraulic cylinders one for each dog, a piston in each of said cylinders interconnected with one of said dogs whereby fluid under pressure may be applied to either side of said piston to effect selective travel of the dogs, a system responsive to movement of said dogs for controlling said machine automatically comprising a high pressure, low volume, output fluid pump; a normally pump pressurized manifold interconnected with the tops and bottoms of said cylinders and said pump to receive fluid from said pump for shifting said opposing dogs, one toward the other for flitch gripping action therebetween; a second manifold normally under lower pressure than said first manifold and interconnected with the bottoms and tops respectively of the cylinders in reverse order of connections with said first manifold; means arresting back flow from said first manifold to said pump to maintain a normal flitch holding pressure; means responsive to a surge in pressure above said normal and said first manifold operating to stop said motor; and

means responsive to a surge in downward pressure in said first manifold operating to stop said motor.

2. In a veneer slicing machine having a vertically reciprocating flitch table driven by a motor, a plurality of pairs of opposing dogs independently shiftable over the table, hydraulic cylinders one for each dog, a piston in each of said cylinders interconnected with one of said dogs whereby fluid under pressure may be applied to either side of said pistons to effect selective travel of the dogs, a system responsive to movement of said dogs for controlling said machine automatically comprising a high pressure, low volume, output fluid pump; a normally pump pressurized manifold interconnected with the tops and bottoms of said cylinders and said pump to receive fluid from said pump for shifting said opposing dogs, one toward the other for flitch gripping action therebetween; a second manifold normally under lower pressure than said first manifold and interconnected with the bottoms and tops respectively of the cylinders in reverse order of connections with said first manifold; means arresting back flow from said first manifold to said pump to maintain a normal flitch holding pressure; means responsive to a surge in pressure above said normal and said first manifold operating to stop said motor; and means responsive to a surge in downward pressure in said first manifold operating to stop said motor; valve means for reversing pump induced fluid pressure from said first manifold to said second manifold to reverse travel of said dogs, one from the other in each of said pairs to have said cylinders exhaust into said first manifold; and means operative by pressure in said second manifold for rendering inoperative said back-flow arresting means.

3. In a veneer slicing machine having a vertically reciprocating flitch table driven by a motor, a plurality of pairs of opposing dogs independently shiftable over the table, hydraulic cylinders one for each dog, a piston in each of said cylinders interconnected with one of said dogs whereby fluid under pressure may be applied to either side of said pistons to effect selective travel of the dogs, a system responsive to movement of said dogs for controlling said machine automatically comprising a high pressure, low volume, output fluid pump; a normally pump pressurized manifold interconnected with the tops and bottoms of said cylinders and said pump to receive fluid from said pump for shifting said opposing dogs, one toward the other for flitch gripping action therebetween; a second manifold normally under lower pressure than said first manifold and interconnected with the bottoms and tops respectively of the cylinders in reverse order of connections with said first manifold; means arresting back flow from said first manifold to said pump to maintain a normal flitch holding pressure; means responsive to a surge in pressure above said normal and said first manifold operating to stop said motor; and means responsive to a surge in downward pressure in said first manifold operating to stop said motor; and means reducing said surge pressure to at least said normal pressure.

4. In a veneer slicing machine having a vertically reciprocating flitch table driven by a motor, a plurality of pairs of opposing dogs independently shiftable over the table, hydraulic cylinders one for each dog, a piston in each of said cylinders interconnected with one of said

dogs whereby fluid under pressure may be applied to either side of said pistons to effect selective travel of the dogs, a system responsive to movement of said dogs for controlling said machine automatically comprising a high pressure, low volume, output fluid pump; a normally pump pressurized manifold interconnected with the tops and bottoms of said cylinders and said pump to receive fluid from said pump for shifting said opposing dogs, one toward the other for flitch gripping action therebetween; a second manifold normally under lower pressure than said first manifold and interconnected with the bottoms and tops respectively of the cylinders in reverse order of connections with said first manifold; means arresting back flow from said first manifold to said pump to maintain a normal flitch holding pressure; means responsive to a surge in pressure above said normal and said first manifold operating to stop said motor; and means responsive to a surge in downward pressure in said first manifold operating to stop said motor; said high surge pressure responsive

means comprising a predetermined pressure opening switch in circuit with said motor and a motor brake control mechanism; said low surge pressure responsive means comprising a second predetermined pressure opening switch in circuit with said motor and said motor brake control system.
